RAILWAY TRAFFIC CONTROLLING
APPARATUS

Herbert A. Wallace, Edgewood, Pa., assignor to
The Union Switch & Signal Company, Swiss-
vale, Pa., a corporation of Pennsylvania

Application September 17, 1941, Serial No. 411,160

8 Claims. (Cl. 246—33)

My invention relates to railway traffic controlling apparatus, and it has particular reference to the organization of such apparatus into railway signal systems of the class employing coded track circuits for controlling either or both wayside signals and train-carried cab signals. More particularly, my invention relates to absolute permissive block (A. P. B.) and other systems for controlling traffic in both directions on a stretch of single track railway, wherein the line wires usually required in such systems are obviated by providing in each track section two track circuits, one for each direction of traffic, arranged to be independent of each other and having their energizations independently coded in accordance with traffic conditions in advance.

An object of my invention is to provide novel and improved absolute permissive block signal systems involving coded track circuits arranged to obviate control line wires.

Another object of my invention is to provide systems of the above-mentioned class arranged to control either or both wayside signals and train-carried cab signals.

A further object is to provide systems of the above-mentioned class involving apparatus arranged to effect the control of train-carried apparatus responsive to track circuit current having certain distinctive characteristics.

An additional object is to provide systems of the above-mentioned class arranged so as to utilize track circuit current having certain distinctive characteristics for the control of train-carried apparatus irrespective of the direction of train movement over the stretch.

The above-mentioned and other important objects and characteristic features of my invention which will become readily apparent from the following description, are attained in accordance with my invention by employing two different frequencies of alternating current one having the frequency commonly used in railway signaling for controlling train-carried apparatus such as cab signals or train control apparatus, and the other having a frequency distinctively different from the one frequency. Each section is provided with two track circuits one supplied at one end of the section with current of the one frequency for transmission through the rails to the other end, and the other track circuit supplied at the other end with current of the other frequency for transmission to the one end of the section. The apparatus further is arranged to control the frequency of current supplied to the circuits of each section so as to supply current of the one

or train control frequency always toward a train on the stretch irrespective of the direction of its movement over the track.

Other objects and advantages of my invention 5 reside in the organization of apparatus into absolute permissive block railway signal systems, as will be made clear in the following description.

I shall describe one form of apparatus embodying my invention, and shall then point out the 10 novel features thereof in claims.

In the accompanying drawings, Figs. 1a to 1g, 15 inclusive, when placed side by side with Fig. 1a on the left, comprise a composite view showing diagrammatically one form of apparatus embodying my invention.

Referring to the drawings, the reference characters 1 and 1a designate the track rails of a stretch of railway track X connected with successive passing sidings Y and Z by switches which 20 are designated by the reference characters W with suitably distinguishing suffixes. Although only one end of siding Y is shown in the drawings, it is to be understood that both ends of this siding are connected with the stretch similarly to 25 siding Z. The rails of the stretch X are divided by insulated joints 2 into a plurality of successive adjoining track sections J—K, K—L, etc.

The reference characters S with distinguishing 30 suffixes designate signals for governing traffic on stretch X. Eastbound traffic, that is, traffic operating from left to right as viewed in the drawings, is governed between sidings Y and Z by signals 2S and 6S, while traffic in the opposite or westbound direction between the two sidings is 35 governed by signals 9S and 5S. Other signals 1S and 10S are provided for governing the entrance of traffic into the siding section extending immediately to the west or to the left of section J—K, and section N—O extending to the right of 40 section M—N, respectively. In addition, signals 13S and 14S are provided at P for governing traffic entering and leaving section O—P, respectively. These signals may be of any desired type, but for the purposes of this description it is 45 assumed that the signals are of the searchlight type each having an operating mechanism such as is shown in United States Letters Patent No. 2,172,724 granted on September 12, 1939 to Wesley B. Wells and William K. Lockhart for Light signals. It is deemed sufficient to state that when 50 the mechanism of a signal S is energized by current of one polarity, it is conditioned to display its clear aspect, when energized by current of the opposite polarity, the signal is conditioned to display its approach aspect, and when the mecha-

nism is deenergized the signal is conditioned to display its stop aspect. Each signal also is provided with an associated circuit controller comprising a movable member 4 which is operated by the associated mechanism into its upper or front position when the signal is conditioned to display either its clear or its approach aspect, and which member is operated by the signal mechanism out of its front and into its back position when the signal is conditioned to display its stop aspect. It is, of course, to be understood that the specific arrangement of signals shown in the drawings is merely illustrative and other arrangements of signals may be employed. For example, additional signals may be provided for the stretch, in pairs, as at locations corresponding to L, or singly if desired.

The wayside signals S are arranged to be controlled in accordance with the usual A. P. B. principle of signaling by apparatus arranged to provide each track section with two track circuits one for each direction of traffic. One of the track circuits of each section is normally supplied with coded track circuit energy of the type adapted to effect control of the usual train-carried apparatus, while the other of the track circuits of each section may be supplied with coded track circuit energy of a distinctive character. Each track circuit includes a track relay, designated by the reference character TR with a suitably distinguishing prefix, and each track relay has associated therewith tuning means hereinafter referred to and controlled in a manner described in detail later whereby each relay TR is conditioned to respond uniquely to the type of current supplied to its associated circuit.

More specifically, each section is supplied at one of its ends with coded alternating track circuit current having the frequency, which I shall refer to as the train control frequency, adapted to effect control of the usual train-carried apparatus. This train-carried apparatus may, for example, be of the type shown in United States Letters Patent No. 1,773,515, granted to C. C. Buchanan on August 19, 1930, and such apparatus is generally tuned to current of a particular frequency (usually 100 cycles per second) distinctively different from the ordinary commercial frequencies, thereby preventing interference with or false operation of the train-carried apparatus due to stray currents of commercial frequencies in the track rails. The other end of each of the sections is normally supplied with coded alternating track circuit current having a frequency distinctively different from the train control frequency and hence ineffective to control the previously mentioned train-carried apparatus. Section J-K, for example, is supplied at its end K with train control current through the medium of a track transformer 3TT having its secondary winding 5 connected to the track rails and having its primary winding 6 connected through a circuit shortly to be traced, to a line transformer LT3 connected across line wires 7 and 8 extending along the trackway. These wires preferably are connected to a suitable source of alternating current, such as a generator not shown but generating alternating current having the previously mentioned train control frequency of 100 cycles per second. The train control energy supplied to section J-K is conducted through the track rails to the other end J of the section to operate the associated track relay 2TR. This relay is supplied with energy derived from the rails through the medium of a relay trans-

former 2RT which has its primary winding 9 connected to the rails and has its secondary winding 10 connected through a rectifier 11 to relay 2TR. The connection of rectifier 11 to relay transformer 2RT is tuned, as shown, by means of a condenser 12 to resonance at the train control frequency. At times, however, this connection may be tuned by means of a condenser 13 to resonance at the other or second frequency, and condenser 12 or 13 is rendered effective to tune such connection to resonance according as contact 14 of the relay 3TP, hereinafter referred to, is in its normal right-hand position, as viewed in Fig. 1a, or is in its reverse (left-hand) position, respectively.

Section J-K also is supplied at its end J with track circuit current of the second frequency through the medium of a track transformer 2TT having its secondary winding 5 connected to the track rails and having its primary winding 6 connected through a circuit shortly to be traced, to a suitable source of current having the second frequency. Current of the other or second frequency may be derived, for example, from a pair of line wires supplied with current of such other frequency, but as shown section J-K is supplied with current of the second frequency from a secondary winding 15 of a transformer FT forming a part of a frequency changer FC, which frequency changer comprises a rectifier 16 having its input terminals connected through line transformer LT1 to the line wires 7 and 8 and having its output terminals connected to primary winding 17 of transformer FT. It is readily apparent that rectifier 16 when energized by current of the first frequency supplies two pulses of unidirectional current to winding 17 of transformer FT in each cycle of alternating current, hence there is induced in secondary winding 15 by these double frequency pulses of unidirectional current, an alternating electromotive force having a frequency which is double the frequency of current in wires 7 and 8. It follows, therefore, that secondary winding 15 of transformer FT may be considered as a source of alternating current having a second frequency of 200 cycles per second, or a frequency distinctively different from the alternating current of the first or train control frequency.

The current of the second frequency supplied to section J-K is conducted through the track rails to the other end K of the section to operate the associated track relay 3TR. This relay is supplied with energy derived from the rails through the medium of a relay transformer 3RT which has its primary winding 9 connected to the rails and has its secondary winding 10 connected through a rectifier 11 to relay 3TR. The connection of rectifier 11 to relay transformer 3RT is tuned, as shown, by means of a condenser 13 to resonance at the second frequency. At times, however, this connection may be tuned by means of condenser 12 to resonance at the first or train control frequency, and condenser 13 or 12 is rendered effective to tune such connection to resonance according as contact 18 of a relay 3SP, hereinafter referred to, is in its normal released position or is in its attracted front position, respectively.

The track circuit currents supplied to each section are coded in the manner usual in coded signal systems. The current of the second frequency supplied at J to section J-K, for example, is coded through the medium of a suitable code transmitter or coder 1CT, which is

represented conventionally in the drawings as comprising a constantly energized winding operating a plurality of contacts 75 and 75a at a rate of 75 times per minute and a plurality of contacts 180 and 180a at a rate of 180 times per minute. The current of the first frequency supplied to section J-K at K is coded in a manner to be explained presently.

The track relays TR of each section have associated therewith code responsive apparatus arranged to respond to frequency type code energy. This code responsive apparatus comprises a decoding transformer, designated by the reference character DT with a suitably distinguishing prefix, a code detecting relay designated by the reference character H with a distinguishing prefix, and certain of the code responsive means include a code selecting relay, designated by the reference character D with a prefix, and a decoding unit DU180.

The decoding transformer 3DT included in the code responsive apparatus associated with relay 3TR of section J-K, for example, has one terminal C of a suitable source of unidirectional current, such as a battery not shown but having its opposite terminals designated by the reference characters B and C, connected to a mid terminal tap of primary winding 21 and has the other terminal B of the source connected to one end or the other of winding 21 according as contact 22 of relay 3TR is in its upper or its released position, respectively. As is readily apparent, the direction of flux in transformer winding 21 is reversed at a rate corresponding to the rate at which relay 3TR operates its contact 22, hence there is induced in the secondary winding 24 of the transformer an alternating electromotive force having a frequency corresponding to the code rate of operation of relay 3TR. Relay 3H associated with transformer 3DT is connected over contact 23 of relay 3TR to secondary winding 24 of the transformer in a manner similar to that described in detail in United States Letters Patent No. 2,237,788, granted on April 8, 1941, to Frank H. Nicholson and Leslie R. Allison, whereby relay 3H is supplied with substantially unidirectional current from transformer 3DT. The relay 3H and transformer 3DT are proportioned and constructed in such manner that relay 3H is effectively energized whenever relay 3TR operates at any of the usual code rates of 75 or more code cycles per minute, but not when relay 3TR operates at a relatively slow code rate of, say, 20 code cycles per minute. Relay 3H accordingly functions as a code detecting relay in that it detects operation of its associated track relay at any of the usual code rates of 75 or more code cycles per minute. Relay 3H associated with relay 3TR has associated therewith a slow releasing relay 3HP controlled over an obvious circuit including front contact 25 of relay 3H.

The code responsive apparatus associated with relay 2TR of section J-K includes, in addition to decoding transformer 2DT and relay 2H arranged in a manner corresponding to that just mentioned, a code selecting relay 2D connected through a decoding unit DU180 to transformer 2DT. The details of construction of decoding unit DU180 are not shown in the drawings, but such a unit usually comprises a reactor condenser tuning unit tuned to resonance at a frequency corresponding to the 180 code rate, whereby relay 2D is effectively energized when and only when the associated relay 2TR operates at the

180 code rate to induce in transformer 2DT an electromotive force having the frequency corresponding to the 180 code rate. Relay 2D accordingly functions as a code selecting relay since it is selectively energized only in response to operation of its associated track relay at the 180 code rate.

The code responsive apparatus associated with relay 1TR of the section immediately to the left, as viewed in Fig. 1a of the drawings, of section J-K includes, in addition to decoding transformer 1DT, code detecting relay 1H and repeater 1HP, and code selecting relay 1D, another or slow code detecting relay BSA and a relay FSA. Relay FSA is arranged with its winding interposed in the circuit connection of front contact 22 of relay 1TR to a portion of primary winding 21 of transformer 1DT, and relay FSA when energized closes its front contact 26 to complete an obvious circuit including relay BSA and over which another portion of winding 21 of transformer 1DT is energized when back contact 22 of relay 1TR is closed. The relays FSA and BSA are preferably sufficiently slow releasing to bridge respectively the "off" and "on" intervals of 20 code energy, hence when relay 1TR operates in response to energy coded at the rate of 20 or more cycles per minute, relay FSA is energized each time relay 1TR closes its front contact 22 in response to an "on" interval of code energy received from the rails of the section, and with front contact 26 of relay FSA closed, relay BSA is energized each time relay 1TR closes its back contact 22 in response to an "off" interval of code in the associated section. When, however, relay 1TR is steadily energized, relay BSA is released since its energizing circuit is then held open at back contact 22 of relay 1TR, or if relay 1TR is steadily released, both relays FSA and BSA are released since relay FSA is deenergized when its energizing circuit is held open at front contact 22 of relay 1TR and with contact 26 of relay FSA open, relay BSA is likewise deenergized. It follows, therefore, that relay BSA is energized when and only when its associated track relay 1TR operates in response to coded energy received from its associated section, and by properly proportioning the release periods of relays FSA and BSA, relay BSA may be employed to detect operation of its associated track relay 1TR in response to energy coded at the rate of 20 or more cycles per minute.

Each signal S is controlled by the decoding apparatus associated with the track relay TR having its prefix corresponding to the prefix employed in the reference character of the signal. For example, signal 1S is controlled by the code responsive apparatus associated with relay 1TR, this control being effective when relays 1H and 1D, associated with relay 1TR, are picked up, to energize the mechanism of signal 1S by current of normal polarity so that signal 1S is caused to display its clear aspect; when relay 1D is released but relay 1H is picked up, the polarity of energy supplied to the mechanism of signal 1S is reversed and the signal is caused to display its approach aspect; and when both relays 1H and 1D are released, the mechanism of signal 1S is deenergized and signal 1S is caused to display its stop aspect.

The reference characters SR with suitably distinguishing suffixes designate stick relays arranged to provide the usual A. P. B. control of the signal apparatus and having pick-up and stick circuits governed by traffic on the stretch. The

circuits and function of the stick relays will be pointed out as the description proceeds. Certain of the stick relays are provided with slow releasing repeater relays, designated by the reference character SP with suitably distinguishing prefixes.

The apparatus embodying my invention further includes relays 3TP, 8TP and 15TP arranged in a manner explained presently to establish overlap control.

In order to simplify the drawings, I have represented contacts of relays at times disposed remote from the relays operating such contacts, but in each case each of such contacts has been represented in the normal condition which it assumes and has been identified not only by a reference character individual to such contacts, but also by placing immediately above such contact the reference character of the relay causing that contact to operate. For example, the reference character 3SP has been placed immediately above back contact 18 to indicate that this contact is operated by relay 3SP, and the contact is represented in a closed position to indicate that such relay is normally deenergized.

As represented in the drawings, the apparatus embodying my invention is in its normal condition, that is, each section represented in the drawings is unoccupied, each section (not shown) between section J—K and the next siding to the west of siding Y is unoccupied and each section (not shown) between section O—P and the next siding east of siding Z is unoccupied. With these various sections mentioned unoccupied, the track circuits of the sections represented in the drawings are supplied with track circuit current coded at the 180 code rate, the track relays TR shown in the drawings are caused to operate at the normal or 180 code rate, the associated code responsive relays D and H are picked up, the signals S are caused to display their respective clear aspects, and the stick relays SR are released.

In this normal condition of the apparatus, relay 1TR associated with the section to the left of section J—K is tuned to respond to current of the train control (100 cycle) frequency and is caused to operate at the 180 code rate in response to energy supplied to the rails of the associated section in a manner corresponding to that hereinafter pointed out whereby the rails of section O—P are supplied at O with track circuit energy. Relays 1D, 1H, 1HP, FSA and BSA associated with relay 1TR accordingly are energized, signal 1S is energized by current of normal polarity and is caused to display its clear aspect, and relay 1SR is released. With relay 1SR released and signal 1S in its clear position, current of the second (200 cycle) frequency coded at the 180 code rate is supplied to section J—K at J over a circuit extending from one terminal of winding 15 of frequency changer FC through contact 21 of relay 3TP in its normal position, contact 180 of coder 1CT, contact 4, operated by signal 1S, in its front position, and secondary winding 6 of track transformer 2TT through a common connection, indicated by the reference character CC, to the other terminal of winding 15. It is to be noted that if contact 21 of relay 3TP is in its reverse or left-hand position and all other parts of the just traced circuit are unchanged, then the secondary winding of line transformer LT1 would be connected to the circuit and current of the first (train control) frequency coded at the 180 code rate would then be supplied at J to section J—K. Likewise, it

is to be noted that if contact 4 of signal 1S is operated from its front to its back position (as when signal 1S is caused to display its stop aspect), then the current supplied at J to section J—K would be carried through contact 75 of coder 1CT and accordingly would be coded at the 75 code rate.

The track circuit current coded at the 180 code rate normally supplied at J to section J—K causes operation of relay 3TR which is tuned by condenser 13 to be responsive to current of the second (200 cycle) frequency. Relays 3H and 3HP associated therewith are energized, and current of the second frequency is supplied at K to section K—L over a circuit extending from one terminal of winding 15 of frequency changer FC through back contact 28 of relay 3SR, front contact 30 (when closed) of relay 3TR, and primary winding 6 of track transformer 4TT through common connection CC to the other terminal of winding 15. It is to be noted that if contact 28 of relay 3SR is operated to its front position, the current supplied over the just traced circuit is then shifted from the second to the first frequency.

The track circuit current normally supplied at K to section K—L is caused to be coded at the 180 code rate in response to relay 3TR following 180 code energy received from its associated section J—K, and this current in section K—L causes relay 5TR to respond since it is tuned by condenser 13 to respond to current of the second frequency. Relays 5D, 5H and 5HP associated with relay 5TR accordingly are energized, and signal 5S is caused to display its normal clear aspect.

Section L—M is supplied at L with current of the first (100 cycle) frequency over a circuit which may be traced from one terminal of the secondary 40 winding of line transformer LT5 through back contact 29 of relay 6SR, contact 180 of coder 2CT, contact 4, operated by signal 5S, in its front position, and primary winding 6 of track transformer 6TT through common connection CC to the other terminal of the secondary winding of transformer LT5. This current is coded at the 180 code rate and causes relay 7TR, tuned by condenser 12 to respond to current of the first frequency, to operate at the 180 code rate and cause its associated 45 relays 7H and 7HP to be picked up. The operation of relay 7TR at the 180 code rate causes the coding at this rate of the current of the first frequency supplied at M to section M—N over a circuit extending from one terminal of line transformer LT7 through back contact 31 of relay 8SR, front contact 30 when closed of relay 7TR, and primary winding 6 of track transformer 8TT through common connection CC to the other terminal of the primary winding of transformer LT7. Relay 9TR at the opposite end N of the section is tuned by condenser 12 to be responsive to this 100 cycle current and relay 9TR is caused to operate at the 180 code rate to energize its associated relays 9D, 9H and 9HP. Signal 9S 55 accordingly is caused to display its normal clear aspect, and section N—O is supplied at N with current of the second (200 cycle) frequency over a circuit extending from one terminal of winding 15 of frequency changer FC through back contact 32 of relay 11SP, contact 180 of coder 3CT, front contact 4 operated by signal 9S and primary winding 6 of track transformer 10TT through common connection CC to the other terminal of winding 15. Relay 11TR at the opposite end O of section N—O is tuned by condenser 13 to be re-

sponsive to current of the second frequency available in the associated section, and relay 11TR accordingly operates at the 180 code rate to cause its associated relays 11H and 11HP to be energized.

Section O—P is supplied at O with current of the first (100 cycle) frequency over a circuit extending from one terminal of the secondary winding of line transformer LT11 through back contact 34 of relay 12SP, back contact 33 of relay 12SR, front contact 30 when closed of relay 11TR, and primary winding 6 of track transformer 12TT through common connection CC to the other terminal of the secondary winding of line transformer LT11. It is to be noted that if relay 12SR operates its contact 33 from its back to its front position, and the other parts of the circuit just traced remain unchanged, then the energy supplied to track transformer 12TT is carried through contact 20 of coder 4CT. This coder is provided with an energizing circuit extending from terminal B through back contact 35 of relay 12SP, front contact 36 of relay 12SR and the winding of coder 4CT to the other terminal C of the source, and coder 4CT when energized operates its contact 20 at a rate of 20 times per minute to thereby code at this rate energy supplied over the previously mentioned circuit including its own contact 26. It follows therefore that under the above assumed conditions, the energy supplied through track transformer 12TT to the rails of section O—P is coded at the 20 code rate.

Relay 13TR at the opposite end P of section O—P is condition by condenser 12 to operate in response to current of the first frequency and relay 13TR operates at the 180 code rate due to the 180 code current normally available in section O—P. Relays 13H, 13HP, 13D, BSA and FSA associated with relay 13TR accordingly are energized, and signal 13S is caused to display its clear aspect.

The section extending to the right or to the east of section O—P is supplied at P with current of the second frequency coded at the 180 code rate, over a circuit corresponding to that previously traced whereby the rails of section J—K are supplied at J with track circuit current. Relay 14TR at end P of the section to the right of section O—P is normally conditioned to respond to current of the train control or 100 cycle frequency, and such relay normally operates at the 180 code rate in response to the 100 cycle current normally supplied to the section in a manner not shown but substantially corresponding to that herein-after described in detail in connection with the supply of track circuit energy at K to section J—K. Relays 14H and 14D associated with relay 14TR are energized, signal 14S is caused to display its clear aspect, and overlap relay 15TP is energized in its normal direction over a circuit not shown but substantially corresponding to the circuit hereinafter traced for relay 3TP.

Section O—P is supplied at P with current of the second frequency coded at the 180 code rate, over a circuit extending from one terminal of secondary winding 15 of frequency changer FC through back contact 44 of relay 13SR, contact 180a of coder 5CT, contact 4 (in its front position) operated by signal 14S, primary winding 6 of track transformer 13TT and common connection CC to the other terminal of winding 15. Relay 12TR at the opposite end O of section O—P is normally tuned by condenser 13 to be responsive to 200 cycle current, and operation of relay 12TR at the 180 code rate causes its associated decoding relays 12H and 12HP to be picked up, and also

causes current of the first frequency to be supplied to section N—O at O over a circuit extending from one terminal of the secondary winding of line transformer LT11 through back contact 38 of relay 11SR, front contact 30 when closed of relay 12TR, and primary winding 6 of track transformer 11TT through common connection CC to the other terminal of the secondary winding of transformer LT11. Relay 10TR at the opposite end N of section N—O is normally tuned by condenser 12 to be responsive to 100 cycle current, and relay 10TR accordingly is normally caused to operate at the 180 code rate to cause its associated relays 10H and 10D to be picked up to control the associated signal 10S to display its normal clear aspect.

Section M—N is supplied at N with current of the second frequency over a circuit extending from one terminal of winding 15 of frequency changer FC through back contact 39 of relay 9SR, contact 180a of coder 3CT, front contact 4 operated by signal 10S, and primary winding 6 of track transformer 9TT through common connection CC to the other terminal of winding 15. Relay 8TR at the opposite end M of the section is tuned by condenser 13 to be responsive to 200 cycle current, and relay 8TR accordingly operates at the 180 code rate to cause its associated relays 8H and 8HP to be energized. Overlap relay 8TP also is energized over an obvious circuit including front contact 57 of relay 8H.

Section L—M is normally supplied at M with 200 cycle current over a circuit extending from one terminal of winding 15 of frequency changer FC through back contact 40 of relay 8SR, front contact 30 when closed of relay 8TR, and primary winding 6 of track transformer 8TT through common connection CC to the other terminal of winding 15. This current is caused to be coded at the 180 code rate in response to operation of relay 8TR by 180 code energy available in section M—N. Relay 6TR at the opposite end L of the section is tuned by condenser 13 to be responsive to 200 cycle current, and relay 6TR accordingly is caused to operate at the 180 code rate to cause its associated relays 6D, 6H and 6HP to be picked up to control the associated signal 6S to display its normal clear aspect.

Section K—L is supplied at L with 100 cycle current over a circuit extending from one terminal of the secondary winding of line transformer LT5 through back contact 41 of relay 5SR, contact 180a of coder 2CT, front contact 4 operated by signal 6S, and primary winding 6 of track transformer 5TT through common connection CC to the other terminal of the secondary winding of transformer LT5. At the opposite end K of the section, relay 4TR is tuned by condenser 12 to be responsive to 100 cycle current, and relay 4TR accordingly is caused to operate normally at its 180 code rate to cause its associated two relays 4H and 4HP to be picked up. Relay 4TR has its contact 30 interposed in a circuit extending from one terminal of the secondary winding of line transformer LT3 through back contact 43 of relay 3SP, front contact 30 when closed of relay 4TR, and primary winding 6 of track transformer 3TT through common connection CC to the other terminal of transformer LT3, and current supplied over this circuit accordingly is normally coded at the 180 code rate, to cause relay 2TR at the opposite end J of the section to operate at the 180 code rate. Relay 2TR, as pointed out heretofore, normally is tuned by condenser 12 to be responsive to 100 cycle current, and relay 2TR oper-

ates in response to the 100 cycle current coded at the 180 code rate available in section J—K to cause its associated relays 2H and 2D to be picked up. Signal 2S is, therefore, normally caused to display its normal clear aspect.

The section extending to the left of section J—K is supplied at J with 200 cycle current over a circuit substantially corresponding to the circuit hereinbefore traced and over which the rails of section O—P are supplied at O with track circuit energy. This current is normally coded at the 180 code rate and is available to cause the track relay (not shown) connected at the opposite end of the section to operate at the 180 code rate. This track relay may, for example, be similar to relay 12TR heretofore mentioned as being provided at O for section O—P.

From the foregoing description, it is apparent that the apparatus embodying my invention is arranged so that the two end sections J—K and M—N of the single track stretch that extends between the two passing sidings Y and Z, are normally supplied with train control current (current having the frequency of 100 cycles per second) which is transmitted through the rails toward the outer ends of such sections. Also, the track circuit apparatus provided for the siding sections is arranged so that 100 cycle current is transmitted through the rails toward the outer ends of such sections.

The apparatus embodying my invention is arranged in accordance with the A. P. B. principle of signaling, so that when a train enters the stretch extending between successive passing sidings, all signals governing opposing traffic movements up to the next passing siding in advance are caused to display their respective stop aspects, while the signals governing traffic in the direction of the train movement are controlled so as to permit following moves under permissive signal aspects governed by traffic conditions in advance. The apparatus further is arranged in such manner that when a train enters the single track stretch between passing sidings, in each of the track sections of the stretch the one track circuit associated with the direction of the train movement is supplied with current of the train control frequency, thereby rendering possible the control train-carried apparatus on the train.

I shall first describe the operation of the apparatus represented in the drawings for a westbound move. When a westbound train enters the first section (not shown) west of the first siding east of siding Z, relay 14TR is caused to become inactive and overlap relay 15TP is caused to reverse its polar contact members 14 and 27, in a manner substantially similar to that hereinafter described whereby relay 2TR is caused to become inactive and overlap relay 3TP is caused to reverse its contact members 14 and 27 when the train enters section M—N. Relay 14TR is thus tuned to be responsive to current of the second (200 cycle) frequency, and current of the train control (100 cycle) frequency is supplied over reverse contact 27 of relay 15TP to the section extending to the right of section O—P.

With relay 14TR inactive, its associated relays 14H and 14D release to cause signal 14S to display its stop aspect, and to cause contact 4 operated thereby to operate from its front to its back position to shift the coding of current supplied at P to section O—P from the 180 to the 75 code rate. Relay 12TR of section O—P accordingly operates at the 75 code rate to repeat this code into section N—O, with the result that

relay 10TR follows this 75 code energy to maintain relay 10H picked up but to release relay 10D. Signal 10S accordingly is caused to display its approach aspect. This condition of the apparatus is maintained until the train enters the section immediately to the east of section O—P, and when this happens, overlap relay 15TP is caused to release, in a manner substantially corresponding to that pointed out hereinafter whereby relay 3TP is caused to release when section J—K is entered by the train. When relay 15TP releases, its contact 86 opens to open the circuit, including contact 4 (in its back position) operated by signal 14S, over which circuit 75 code energy is supplied at P to section O—P. Section O—P is thus deprived of 200 cycle current normally supplied at P, and relay 12TR becomes inactive, thereby maintaining open its contact 30 and removing the 100 cycle current from section N—O with the result that relay 10TR also becomes inactive to in turn cause a release of its associated relay 10H. Signal 10S accordingly is caused to display its stop aspect, and operates its contact member 4 from its front to its back position to shift the coding of the current supplied at N to section M—N from the 180 to the 75 code rate. Relay 8TR at the opposite end M of section M—N of course operates at the 75 code rate to code at this rate the energy supplied at M to section L—M, and relay 6TR at L also operates at the 75 code rate with the result that its associated relay 6D releases and its associated signal 6S is caused to display its approach aspect.

The inactivity of relay 12TR of the section to the left of section N—O, causes its associated relays 12H and 12D to release. Relay 11SR is now energized over a pick-up circuit which may be traced from terminal B through back contact 25 of relay 12H, front contact 51 of relay 11HP, the winding of relay 11SR, and back contact 80 of relay 12SR to the other terminal C. Relay 11SR picks up to close its front contact 52 to prepare a stick circuit, and operates its contact 53 from its back to its front position to shift the tuning of relay 11TR from 200 to 100 cycle current. Contact 54 of relay 11SR also closes to energize overlap relay 11SP, which relay picks up to operate its contact 55 from its back to its front position to shift the tuning of relay 10TR from 100 cycle to 200 cycle current, and also operates its contact 32 from its back to its front position to shift the frequency of current supplied at N to section N—O from 200 cycles to 100 cycles. At this time, therefore, section N—O is supplied at N with 100 cycle current coded at the 180 code rate, relay 11TR is tuned to respond to 100 cycle current and follows the 180 code energy available in section N—O to code at this rate the 100 cycle energy supplied at O to section O—P, and relay 10TR is tuned to respond to 200 cycle current but is inactive due to the fact that relay 12TR is inactive and holds its front contact 30 open to constantly interrupt the circuit over which current normally is supplied at O to section N—O. It follows, therefore, that in the siding sections, that is, sections N—O and O—P, current of a train control frequency is supplied in the direction toward a westbound train and hence is available to operate train-carried apparatus on such train.

When the westbound train enters section O—P, relay 13TR is shunted, relays FSA, BSA, 13H, 13HP and 13D are released, and signal 13S is caused to display its stop aspect. Relay 11TR is shunted and relays 11H and 11HP associated

therewith are released when the train enters section N—O, and relay 11SR is held energized over a stick circuit which extends from terminal B through back contact 51 of relay 11HP, front contact 52 and the winding of relay 11SR, and back contact 60 of relay 12SR to terminal C.

As will be made clear hereinafter, the apparatus associated with the section to the right of section O—P is restored, when the train vacates the section, to its normal condition wherein overlap relay 15TP is caused to close its front contact 86 and operate its polar contacts 14 and 27 to their normal right-hand positions to tune relay 14TR to respond to current of the train control (100 cycle) frequency and to cause current of the second (200 cycle) frequency to be supplied at P to the associated section.

When the train enters section M—N, relay 8TR is shunted and its associated relays 9D, 9H and 9HP are released to cause the associated signal 9S to display its stop aspect. Relay 8TR at the opposite end M of the section also is shunted, its associated relays 8H and 8HP are released, and overlap relay 8TP quickly releases to open its contact 103 interposed in a pick-up circuit, presently to be traced, of relay 9SR, prior to that relay picking up at the end of its slow pick-up period. Relay 7SR at location M is energized over a pick-up circuit extending from terminal B through back contact 25 of relay 8H, front contact 59 of relay 7HP and the winding of relay 7SR through back contact 60 of relay 8SR to terminal C. Relay 7SR accordingly picks up to close its front contact 61 and thereby prepares a stick circuit hereinafter mentioned.

With relay 8TR of section M—N shunted, its front contact 30 is held steadily open to deprive section L—M of energy normally applied thereto at M. Relay 6TR at the opposite end of section L—M thereupon becomes inactive, and its associated relays 6H and 6HP release to cause signal 6S to display its stop aspect. Signal 6S accordingly operates its contact 4 from its front to its back position, and with relay 6SR released, the circuits previously mentioned over which section K—L is supplied at L with track circuit energy are opened so that no track circuit energy is supplied to section K—L at L. Relay 5SR at location L becomes energized over a pick-up circuit extending from terminal B through back contact 25 of relay 6H, front contact 63 of relay 5HP, the winding of relay 5SR and back contact 64 of relay 6SR to the other terminal of the source. Relay 5SR picks up to close its front contact 65 to complete a stick circuit path connected in multiple with contact 63 of relay 5HP.

When signal 6S at L operates its contact 4 from its front to its back position, as pointed out hereinbefore, to thereby deprive section K—L of the track circuit energy normally supplied at L to such section, relay 4TR at the opposite end K of the section becomes inactive, relays 4H and 4HP associated therewith release, and relay 3SR picks up over its pick-up circuit extending from terminal B through back contact 25 of relay 4H, front contact 71 of relay 3HP, the winding of relay 3SR, and back contact 72 of relay 4SR to terminal C. The inactivity of relay 4TR of course causes that relay to maintain its front contact open, thereby depriving section J—K of the track circuit energy normally applied at K to the section, and causing relay 2TR to become inactive. Relays 2H and 2D accordingly release, and signal 2S is caused to dis-

play its stop aspect and operate its contact 4 to its back position to shift the coding of current supplied at J to the section to the left of section J—K, from the 180 to the 75 code rate.

As mentioned previously, relays 5SR and 3SR at locations L and K, respectively, are energized. Relay 5SR in picking up closes its front contacts 69 to shift the tuning of relay 5TR to current of the first frequency, while relay 3SR picks up to close its front contacts 70 and 28 to shift, respectively, the tuning of relay 4TR to current of the second frequency, and the current supplied at K to section K—L to the first frequency. Front contact 78 of relay 3SR also closes to energize relay 3SP over an obvious circuit, and front contacts 76 and 77 of relay 3SR close in addition to reverse the polarity of current supplied to overlay relay 3TP. This latter relay is normally energized by current of what I shall term normal polarity supplied over a circuit extending from terminal B through back contact 76 of relay 3SR, front contact 85 of relay 3H, the winding of relay 3TP and back contact 77 of relay 3SR to terminal C, and it is readily apparent from an inspection of the drawing that when front contacts 76 and 77 of relay 3SR close, the polarity of current energizing relay 3TP is reversed. Relay 3TP is therefore caused to shift its polar contacts 14 and 27 to their respective reverse positions to tune relay 2TR to respond to current of the second frequency, and cause the current supplied at J to section J—K to be shifted to the first frequency.

The slow pick-up characteristics of relay 3SP are selected so that relay 3SP picks up to close its front contact 18 at substantially the same instant that relay 3TP reverses its polar contacts 14 and 27. Front contact 18 of relay 3SP conditions condenser 12 to tune relay 3TR to respond to current of the first frequency. It follows, therefore, that when relays 5SR, 3SR and 3SP are energized and relay 3TP is energized by current of reverse polarity, the track circuit apparatus of sections J—K and K—L are conditioned to supply current of the first or train control frequency toward a westbound train on the stretch, thereby rendering possible the control of train-carried apparatus on the train.

From the foregoing description, it is readily apparent that when a westbound train enters the single track stretch extending between the two passing sidings Y and Z, all of the opposing signals up to the next passing siding Y are caused to display their stop aspects to prevent opposing moves, and the track circuit energies supplied to the sections of the stretch are controlled in such manner as to supply current of the train control frequency to each of the sections in the direction toward an approaching westbound train.

When the westbound train vacates section O—P, relay 12TR is caused to operate in a manner to be made clear presently, and relays 12H and 12HP associated therewith are picked up. Relay 11SR is now held energized over its stick circuit including back contact 51 of relay 11HP, and section N—O is supplied at O with 200 cycle current coded at a rate corresponding to the rate of operation of relay 12TR, this energy being supplied over a circuit including winding 15 of frequency changer FC, front contact 38 of relay 11SR, and contact 30 (when closed) of relay 12TR. As will be made clear presently, relay 12TR is caused to operate at this time at

the 180 code rate, hence 180 code energy is supplied to section N—O but is shunted by the train away from relay 10TR. When, however, the train vacates section N—O, relay 10TR operates at the 180 code rate, being tuned at this time by condenser 13 to respond to 200 cycle current, and relays 10H and 10D are picked up to cause signal 10S to display its clear aspect. Contact 4 associated with signal 10S accordingly is operated from its back to its front position, and 180 code energy of the second frequency is supplied at N to section M—N, but this energy is at this time shunted by the train away from relay 8TR.

When the train enters section L—M, relay 7TR is shunted, relays 7H and 7HP release, and relay 7SR is stuck energized over a stick circuit including back contact 69 of relay 7HP, and front contact 61 and the winding of relay 7SR. This stick circuit holds relay 7SR picked up after the train vacates section M—N and relay 8TR operates, in response to the 180 code energy of the second frequency available in section M—N, to pick up the associated relays 8H and 8HP. Relay 8TP also is caused to pick up to close its front contact 81 interposed in the previously mentioned circuit including contact 75 of coder 8CT, front contact 32 of relay 11SP, and contact 4 (in its back position) operated by signal 9S, over which circuit 75 code energy of the first frequency is applied at N to section N—O. This energy causes relay 11TR to operate at the 75 code rate and pick up its associated relays 11H and 11HP, and release stick relay 11SR. Front contact 54 of relay 11SR accordingly opens to deenergize relay 11SP, whereupon contact 32 of relay 11SP operates from its front to its back position to shift the frequency of energy applied at N to section N—O from the train control (or first) frequency to the second frequency. Contact 55 of relay 11SP also operates from its front to its back position to shift the tuning of relay 10TR from the second to the first frequency.

The release of relay 11SR, at location O, also causes operation of its contact 53 from its front to its back position to shift the tuning of relay 11TR from the first to the second frequency, and contact 38 of relay 11SR operates from its front to its back position to shift the current supplied at O to section N—O from the second to the first frequency. It follows, therefore, that when a westbound train passes location M, the track circuit energies supplied to section N—O are restored to their normal condition, that is, the track circuit apparatus of section N—O is restored to the condition wherein relay 10TR responds to current of the first frequency supplied at the opposite end of the section, and relay 11TR responds to current of the second frequency supplied to the section at end N. This current of the second frequency is coded at the 75 code rate and hence causes relay 11TR to operate and code at a corresponding rate the energy of the first frequency applied at O to section O—P. Relay 13TR accordingly responds to this 75 code energy available in section O—P and picks up relays FSA, BSA, 13H and 13HP, thereby causing signal 13S to display its approach aspect. It is to be noted that relay 13SR is provided with slow pick-up characteristics so selected that relay 13SR does not pick up even though relay BSA, at this time, picks up to close its front contact 94 while back contact 93 of relay 13HP, interposed in a circuit hereinafter traced for relay 13SR, is closed.

When the train enters section K—L, relay 5TR is shunted, relays 5D, 5H and 5HP associated therewith release so that signal 5S is caused to display its stop aspect, and back contact 63 of relay 5HP closes to complete the previously mentioned stick circuit for relay 5SR, which circuit extends from terminal B through back contact 63 of relay 5HP, front contact 65 and the winding of relay 5SR, and back contact 64 of relay 6SR to the other terminal C.

After the train vacates section L—M, relay 7TR responds to 75 code energy supplied at L to the section over a circuit including back contact 29 of relay 6SR, contact 75 of coder 2CT, front contact 90 of relay 5SR, and contact 4 (in its back position) operated by signal 5S. Operation of relay 7TR at this 75 code rate is effective to repeat the 75 code energy into section M—N, and relay 9TR operates to pick up relays 9H and 9HP, thereby causing signal 9S to display its approach aspect, and causing operation of contact 4 of signal 9S from its back to its front position to shift the coding of current supplied to section N—O from the 75 to the 180 code rate. This 180 code energy is repeated by relay 11TR into section O—P to cause operation of relay 13TR at the 180 code rate. Relay 130 accordingly is picked up and signal 13S is caused to display its clear aspect.

In addition, when the train vacates section L—M, relay 6TR is caused to operate at the 180 code rate in response to energy of the second frequency repeated into section L—M at M due to the operation of relay 8TR in response to 180 code energy available in section M—N. Relays 6H, 6HP and 6D are therefore energized, and signal 6S is caused to display its clear aspect and operate its contact 4 from its back to its front position, thereby completing an easily traced circuit over which energy of the second frequency coded at the 180 code rate is supplied at L to section K—L. This energy is, of course, shunted away from relay 4TR while the train occupies section K—L.

When the westbound train enters section J—K, relay 3TR is shunted and relays 3H and 3HP associated therewith release. Back contact 71 of relay 3HP closes to complete a stick circuit for relay 3SR, which circuit extends from terminal B through back contact 71 of relay 3HP, front contact 73 and the winding of relay 3SR, and back contact 72 of relay 4SR to terminal C. In addition, front contact 85 of relay 3H opens to open the previously traced circuit of relay 3TP, whereupon relay 3TP releases to open its front contact 86 interposed in the circuit previously traced and over which 75 code energy is supplied at J to the section to the left of section J—K. It is thus apparent that when the section at the exit end of the stretch is entered by the train, as for example, when section J—K is entered by the westbound train, the section in advance for the direction of train movement is then deprived of track circuit energy. This deprivation of energy may be utilized to place at stop the opposing signal at the opposite end of siding Y, in a manner substantially corresponding to that hereinbefore described whereby signal 16S is placed at stop when the westbound train enters the section to the right of section O—P and deprives section O—P of energy by opening contact 86 of overlap relay 15TP. It follows, therefore, that apparatus embodying my invention is arranged so as to provide the usual overlap protection at the passing sidings.

The 180 code energy of the second frequency is,

of course, available to cause operation of relay 4TR after the train vacates section K—L. When this happens, relays 4H and 4HP are picked up, but relay 3SR is retained energized over its previously traced stick circuit. It is to be noted that each stick relay 3SR and 4SR at location K (and the corresponding stick relays at locations L, M, and O also) is arranged to be energized over a back contact of the other stick relay, hence when one stick relay is energized it prevents energization of the other.

When the train enters the section extending to the left of section J—K, relay 1TR is shunted and the associated relays 1D, 1H, 1HP, FSA and BSA are released. Signal 1S accordingly is caused to display its stop aspect, and operates its contact 4 from its front to its back position.

The previously mentioned operation of relay 4TR causes 180 code current of the second frequency to be repeated into section J—K over a circuit comprising winding 15 of frequency changer FC, front contact 43 of relay 3SP, contact 30 when closed of relay 4TR and winding 6 of transformer 3TT. This energy is of course shunted by the train away from relay 2TR at this time, but when the train vacates section J—K, this energy causes operation of relay 2TR at the 180 code rate and picks up relays 2H and 2D to cause signal 2S to display its clear aspect and operate its contact 4 to its front position. The previously traced circuit over which 180 code, 200 cycle current is supplied at J to the section to the left of section J—K is now completed, to condition the relay of such section to operate at the 180 code rate when the train vacates such section. Such relay is, therefore, conditioned to operate at the 180 code rate in a manner corresponding to that previously mentioned whereby relay 12TR is caused to operate at the 180 code rate when the westbound train vacates section O—P.

At the time that the train vacates section J—K, current of the first (100 cycle) frequency is supplied at J to section J—K over a circuit previously traced and comprising contact 4 (in its back position) operated by signal 1S, contact 75 of coder 1CT, and contact 27 of relay 3TP in its reverse position. This 75 code energy available in section J—K operates relay 3TR, and is repeated by that relay into section K—L where it causes operation of relay 5TR. At location K, relays 3H and 3HP are picked up and relay 3SR is released, while at location L, relays 5H and 5HP are picked up and relay 5SR is released. The release of relay 3SR shifts the tuning of relay 4TR from 200 to 100 cycle current and shifts the frequency of current supplied at K to section K—L from 100 to 200 cycles. Similarly, the release of relay 5SR alters the tuning of relay 5TR from 100 to 200 cycle current, and changes the frequency of current supplied at L to section K—L from 200 to 100 cycles. In addition, the energization of relay 5H causes signal 5S to display its approach aspect and operate its associated contact 4 from its back to its front position to alter the coding of the current supplied at L to section L—M from the 75 to the 180 code rate. This 180 code energy is repeated by relay 7TR into section M—N where it causes relay 9TR to pick up relay 9D and thus cause signal 9S to display its clear aspect.

Considering location K again, the release of relay 3SR causes its front contact 73 to open and deenergize relay 3SP, and its back contacts 76 and 77 to close and energize relay 3TP with

energy of normal polarity. Relay 3TP thereupon closes its front contact 86, and shifts its polar contacts 14 and 27 from their reverse to their normal positions to shift, respectively, the tuning of relay 2TR to 100 cycle current and the frequency of current supplied at J to section J—K to 200 cycle current. Relay 3SP also releases to close its back contacts 13 and 43 at substantially the same instant that polar contacts 14 and 27 of relay 3TP assume their respective normal positions. Back contact 18 of relay 3SP conditions relay 3TP to operate in response to 200 cycle current, and back contact 43 of relay 3SP shifts the frequency of current supplied at K to section J—K from 200 to 100 cycles.

From the foregoing, it is readily apparent that after the westbound train proceeds through sections J—K and K—L, the track circuit apparatus of these sections are restored to their normal condition, that is, relays 2TR and 4TR are tuned to respond to current of the first frequency supplied at the opposite ends of the sections, and relays 3TR and 5TR are tuned to respond to current of the second frequency supplied to their respective track circuits.

When relay 1TR is caused to operate in response to 75 code energy made available in its associated section in the manner described in detail in connection with the corresponding section O—P, the associated signal 1S is caused to display its approach indication, and its associated circuit controlling contact 4 is operated from its back to its front position to shift the code rate of energy supplied at J to section J—K from the 75 to the 180 code rate. This causes relay 3TR to operate at the 180 code to code at this rate the energy supplied at K to section K—L, and relay 5TR associated with section K—L is caused to operate at the 180 code to energize its associated relay 5D, thereby causing the associated signal 5S to display its clear aspect.

Signal 1S is caused to display its clear aspect, and the apparatus is restored to its normal condition, as represented in the drawings, when relay 1TR is caused to operate at the 180 code rate in response to energy made available in its associated section in a manner substantially corresponding to that described in detail hereinbefore in connection with the corresponding section O—P.

From the foregoing description, it is readily apparent that I have provided railway traffic controlling apparatus so arranged as to permit a westbound train to move over a single track stretch provided with signals controlled by the movement of the train in such manner as to prevent opposing eastbound moves while permitting following westbound moves under permissive signal aspects governed by traffic conditions in advance. In addition, it is apparent that the track circuit energies supplied to the sections of the stretch are so controlled that in each section, current of the train control frequency is supplied to the section in a direction so as to be transmitted toward the train, thereby rendering possible the control of train-carried apparatus on the train uniquely responsive to current of the train control frequency.

I shall now assume that with the apparatus represented in the drawings in its normal condition, an eastbound train enters the first section east of the first siding west of siding Y. When this happens, the track circuit energy normally available in the section to the left of section

J—K is shifted from the normal 180 code rate to the 75 code rate, in a manner substantially similar to that hereinafter explained whereby the code rate of the energy supplied to section O—P is shifted from the 180 code rate to the 75 code rate when the train enters section J—K. Under the assumed conditions, relay 1TR is caused to operate at the 75 code rate and relay 1D associated therewith releases to cause the associated signal 1S to display its approach aspect. This condition of the apparatus is maintained until the train occupies the section to the left of siding section Y, whereupon the code rate of energy available in the section to the left of section J—K is shifted, in a manner to be made clear hereinafter, from the 75 to the 20 code rate, thereby causing operation of relay 1TR at the 20 code rate, and releasing relays 1H and 1HP. Signal 1S at J accordingly is caused to display its stop aspect, contact 4 operated thereby assumes its back position to shift the coding of energy applied at J to section J—K from the 180 to the 75 code rate, relays 3TR and 5TR operate at the 75 code rate, and relay 5D releases to cause signal 5S to display its approach aspect.

At location J, relay 1SR is picked up over a pick-up circuit extending from terminal B through back contact 93 of relay 1HP, front contact 94 of relay BSA and the winding of relay 1SR to terminal C. Relay 1SR closes its front contact 95 to thereby prepare a stick circuit hereinafter traced, operates its contact member 96 from its back to its front position to shift the tuning of relay 1TR from 100 cycle to 200 cycle current, and operates its contact member 44 from its back to its front position to shift the frequency of current supplied at J to the section to the right of section J—K from 200 to 100 cycle current. This 100 cycle current is of course available when the train occupies the section to the left of section J—K to cause operation of the train-carried apparatus. When the train occupies this section, relay 1TR is deenergized and inactive, and relays FSA and BSA associated therewith are released to complete the previously mentioned stick circuit of relay 1SR, which circuit extends from terminal B through back contact 93 of relay 1HP, back contact 94 of relay BSA, front contact 95 and the winding of relay 1SR to terminal C.

When the train enters section J—K, relay 2TR is shunted and relays 2H and 2D associated therewith are released to cause signal 2S to display its stop aspect. In addition, relay 3TR is shunted and relays 3H, 3HP and 3TP associated therewith are released. Relay 4SR now becomes energized over a pick-up circuit extending from terminal B through back contact 25 of relay 3H, front contact 98 of relay 4HP, the winding of relay 4SR and back contact 78 of relay 3SR to terminal C.

With relay 3TR inactive, its contact 39 is held continuously open to open the previously traced circuit over which 200 cycle current normally is supplied at K to section K—L. Relay 5TR at the opposite end L of the section accordingly becomes inactive, relays 5H and 5HP associated therewith release, signal 5S is caused to display its stop aspect, and relay 6SR is picked up over a pick-up circuit extending from terminal B through back contact 25 of relay 5H, front contact 99 of relay 6HP, the winding of relay 6SR and back contact 100 of relay 5SR to terminal C.

When signal 5S at L operates to its stop position, its associated contact member 4 operates

from its front to its back position. This opens the circuit previously traced over which section L—M is supplied at L with track circuit energy, with the result that relay 7TR becomes inactive, and its associated relays 7H and 7HP release. Relay 8SR now becomes energized over a pick-up circuit extending from terminal B through back contact 25 of relay 7H, front contact 101 of relay 8HP, the winding of relay 8SR and back contact 102 of relay 7SR to terminal C.

The inactivity of relay 7TR causes its front contact 30 to remain open, thereby opening the previously traced circuit over which section M—N is supplied at M with track circuit energy. Relay 9TR accordingly is caused to become inactive, and relays 9D, 9H and 9HP associated therewith are released to cause signal 9S to display its stop aspect. Relay 9SR becomes energized, during the slow release interval of repeater relay 9HP, over a pick-up circuit including back contact 25 of relay 9H, front contact 62 of relay 9HP, front contact 103 of relay 8TP and the winding of relay 9SR to terminal C.

With signal 9S at N caused to display its stop aspect, its associated contact member 4 is operated from its front to its back position to shift the coding of current supplied at N to section N—O from the normal 180 code rate to the 75 code rate. This 75 code energy is supplied at N to section N—O over a circuit comprising winding 15 of frequency changer FC, back contact 32 of relay 11SP, contact 75 of coder 3CT, front contact 81 of overlap relay 8TP, contact 4 in its back position, operated by signal 9S, and winding 6 of transformer 10TT, and this energy causes operation of relay 11TR at a corresponding rate to repeat this 75 code current into section O—P, as is readily apparent from an inspection of the drawings. The 75 code current in section O—P operates relay 13TR and releases relay 13D to cause the westbound signal 1S at the opposite end of siding Z to display its approach aspect, as pointed out heretofore.

As mentioned previously, relays 6SR, 8SR and 9SR at locations L, M and N, respectively, are energized. The energization of relay 6SR causes its contact member 104 to be operated from its back to its front position to shift the tuning of relay 6TR from 200 to 100 cycle current, and also operates its contact member 29 from its back to its front position to shift the frequency of current supplied at L to section L—M from 100 to 200 cycle current. The energization of relay 8SR causes its contact member 107 to be operated from its back to its front position to shift the tuning of relay 7TR from 100 to 200 cycle current, and also to operate its contact member 40 from its back to its front position to shift the frequency of current supplied at M to section L—M from 200 to 100 cycle current. In addition, relay 8SR operates its contact member 109 from its back to its front position to shift the tuning of relay 8TR from 200 to 100 cycle current.

The energization of relay 9SR is effective to operate its associated contact member 110 from its back to its front position to shift the tuning of relay 9TR from 100 to 200 cycle current, and also causes contact member 39 of relay 9SR to operate from its back to its front position to shift the frequency of current supplied at N to section M—N from 200 cycles to 100 cycles. It is readily apparent, therefore, that in sections L—M and M—N, the track circuit apparatus is controlled in response to the entrance of an eastbound train on section J—K in such manner as to supply

such sections with track circuit energy of train control frequency in such manner as to be transmitted through the rails of such sections toward an eastbound train.

When the train vacates the section to the left of section J—K, relay 1TR is caused to remain inactive, in a manner substantially corresponding to that hereinafter described in detail whereby relay 13TR remains inactive after the eastbound train vacates section O—P. Signal 1S accordingly continues to display its stop aspect and maintains its contact 4 in its back position to complete a circuit previously mentioned and comprising winding 15 of frequency changer FC, contact 27 of relay 3TP in its normal position, contact 75 of coder 1CT, back contact 4 operated by signal 1S and winding 6 of transformer 2TT. Current of the second frequency coded at the 75 code rate is, therefore, supplied at J to section J—K but is shunted by the train away from relay 3TR. At this time, however, the rails of the section to the left of section J—K are not supplied at J with track circuit energy, since contact 4 operated by signal 2S is in its back position, and front contact 86 of relay 3TP is open.

Relay 4TR is shunted, and relays 4H and 4HP release, when the train enters section K—L. Relay 4SR is now held energized over its stick circuit comprising back contact 98 of relay 4HP, front contact 97 and the winding of relay 4SR, and back contact 78 of relay 3SR. After the train vacates section J—K, relay 3TR operates in response to the 75 code energy available in the section, and repeats this energy into section K—L where it is shunted by the train. Operation of relay 3TR is, however, effective to cause relays 3H, 3HP and 3TP to pick up, whereupon front contact 86 of relay 3TP closes and 75 code energy of the first frequency is supplied at J to the section to the left of section J—K. This energy functions to restore the track circuit apparatus of the associated section to its normal condition, in a manner substantially corresponding to that hereinafter described in detail whereby the track circuit apparatus of section O—P is restored to its normal condition when 75 code energy of the first frequency is applied at P to section O—P after the eastbound train has vacated the section to the right of section O—P. At this time, however, it is deemed sufficient to state that after the 75 code energy is supplied to the section to the left of section J—K, relay 1TR is caused to operate at the 180 rate in response to energy of the second frequency, relays FSA, BSA, 1H, 1HP and 1D are picked up, and signal 1S is caused to display its clear aspect and operates its contact 4 to its front position, thereby shifting the energy supplied at J to section J—K from the 75 to the 180 code rate and causing relay 3TR to repeat this 180 code into section K—L. In addition, relay 1SR at J releases when relay 1HP opens its back contact 93, and relay 1SR closes its back contact 96, to tune relay 1TR to respond to current of the first frequency, and its back contact 44, to shift the current supplied at J to the rails of the section associated with relay 1TR, from the first to the second frequency. As will be made clear presently, relay 1TR continues to operate at the 180 code rate in response to energy of the first frequency made available in the section.

When the train enters section L—M, relay 6TR is shunted, its associated relays 6D, 6H and 6HP release, signal 6S is caused to display its stop aspect and operates its contact 4 to its back position, and relay 6SR is held energized over its

stick circuit comprising back contact 99 of relay 6HP, front contact 105 and the winding of relay 6SR, and back contact 100 of relay 5SR. After section K—L becomes vacated, relay 5TR operates at the 180 code rate in response to energy repeated by relay 3TR into section K—L, and relays 5H, 5HP and 5D pick up to cause signal 5S to display its clear aspect and operate its contact 4 to its front position. The rails of section L—M are, therefore, supplied at this time with current of the second frequency coded at the 180 code rate, but the train in the section shunts the energy away from relay 7TR.

Section K—L is also supplied at this time with 75 code energy of the first frequency, over a circuit comprising the secondary winding of line transformer LT5, back contact 41 of relay 5SR, contact 75a of coder 2CT, front contact 106 of relay 6SR, contact 4, in its back position, of signal 6S, and winding 6 of transformer 5TT. Relay 4TR accordingly is caused to operate and repeat this 75 code energy into section J—K to cause operation of relay 2TR at the 75 code rate. Relays 4H and 4HP associated with relay 4TR are picked up, while stick relay 4SR is released. At location J, relays 2H and 2D associated with relay 2TR are picked up, and signal 2S is caused to display its approach aspect and operates its contact 4 to its front position to shift the coding of current supplied at J to the section to the left of section J—K from the 75 to the 180 code rate. When the eastbound train enters section M—N, relay 8TR is shunted and its associated relays 8H and 8HP release, relay 8SR now being held energized over its stick circuit extending from terminal B through back contact 101 of relay 8HP, front contact 111 and the winding of relay 8SR, and back contact 102 of relay 7SR to terminal C. The release of relay 8H opens its front contact 57 to deenergize relay 8TP, with the result that front contact 81 of relay 8TP opens to open the previously traced circuit over which current of the second frequency coded at the 75 code rate is supplied at N to section N—O. Relay 11TR accordingly becomes inactive, and relays 11H and 11HP associated therewith release. Relay 12SR now becomes energized over a circuit extending from terminal B through back contact 25 of relay 11H, front contact 74 of relay 12HP, the winding of relay 12SR, and back contact 82 of relay 11SR to terminal C. Relay 12SR picks up and closes its front contact 113 to energize relay 12SP, operates its contact 33 from its back to its front position, and closes front contact 36 to energize coder 4CT. Under the assumed conditions, current of the first frequency coded at the 20 code rate is supplied at O to section O—P over a circuit extending from one terminal of the secondary winding of the line transformer LT11 through back contact 34 of relay 12SP, front contact 33 of relay 12SR, contact 20 of coder 4CT, and primary winding 6 of track transformer 12TT through common connection CC to the other terminal of the secondary winding of line transformer LT11. This 20 code current available in section O—P causes operation of track relay 13TR at the opposite end at the 20 code rate, and thereby causes the associated relays 13H and 13HP to be released and signal 13S to display its approach aspect to provide the usual overlap protection. Stick relay 13SR now is energized over a circuit extending from terminal B through back contact 93 of relay 13HP, front contact 94 of relay BSA and the winding of relay 13SR to terminal C. When relay 13SR picks up,

it operates its back contact 96 to its front position to shift the tuning of relay 13TR from 100 to 200 cycle current, and also operates its contact member 44 from its back to its front position to shift the frequency of current supplied at P to section O—P from 200 to 100 cycle current.

The slow acting characteristics of relay 12SP at O are selected so that relay 12SP picks up to operate its contact member 114 from its back to its front position to shift the tuning of relay 12TR from 200 to 100 cycle current, and to open its back contact 34 interposed in the circuit over which 200 cycle current is normally supplied to section O—P, at substantially the same time that relay 13SR is caused to pick up. When back contact 34 of relay 12SP opens, relay 13TR becomes inactive, and relays FSA and BSA associated therewith release. Relay 13SR is now held energized over an obvious stick circuit including back contact 93 of relay 13HP, back contact 94 of relay BSA and front contact 95 of relay 13SR. Relay 12TR of section O—P, is however caused to operate at the 180 code rate in response to current of the first frequency supplied at P to section O—P, and relay 12TR functions to repeat this 180 code current into section N—O to cause operation at a corresponding rate of relay 10TR. Relays 10H and 10D accordingly are energized and cause signal 10S to display its clear aspect.

After the train vacates section L—M, relay 7TR operates at the 180 code rate in response to the current supplied at L to section L—M. Relays 7H and 7HP are picked up, and relay 7TR repeats the 180 code current into section M—N, but this current is shunted by the train away from relay 9TR.

When the train enters section N—O, relay 10TR is shunted, its associated relays 10H and 10D are released, and signal 10S is caused to display its stop aspect. Contact 4 operated by signal 10S accordingly assumes its back position, and after the train vacates section M—N, that section is supplied with current of the first frequency coded at the 75 code rate over a circuit including contact 4 operated by signal 10S in its back position, contact 75 of coder 3CT, and front contact 39 of relay 9SR. This 75 code energy causes relay 8TR to operate at the 75 code rate, and relay 8TR functions to repeat this 75 code energy into section L—M, thereby causing relay 6TR to operate at the 75 code rate to pick up its associated relays 6H and 6HP. Signal 6S is caused to display its approach aspect and operates its contact 4 to its front position to shift the coding of current supplied at L to section K—L from the 75 to the 180 code rate. Relay 4TR accordingly operates and repeats this energy into section J—K, whereupon relay 2TR operates and picks up its associated relay 2D to cause signal 2S to display its clear aspect.

At this time, relay 9TR is caused to operate at the 180 code rate in response to energy repeated by relay 7TR into section M—N, and relays 9H, 9HP and 9D are picked up to cause signal 9S to display its clear aspect and operate its contact 4 to its front position. Energy of the second frequency coded at the 180 code rate is supplied at N to section N—O but is shunted by the train away from relay 11TR.

The track circuit apparatus of sections L—M and M—N are also restored to their normal condition at this time, in response to the release of relays 6SR, 8SR and 9SR. Relay 6SR releases when relay 6HP at L picks up, and back contacts 104 and 29 of relay 6SR close to shift, re-

spectively, the tuning of relay 6TR to current of the second frequency, and the frequency of current supplied at L to section L—M to the first frequency. Relay 8SR at M releases when relays 8H, 8HP and 8TP associated with relay 8TR pick up in response to operation of relay 8TR, and back contacts 107 and 40 of relay 8SR close to shift, respectively, the tuning of relay 7TR to current of the first frequency, and the frequency of current supplied at M to section L—M to the second frequency. Back contacts 109 and 31 of relay 8SR also close so that relay 8TR is tuned to respond to current of the second frequency, and current of the first frequency is applied at M to section M—N. Relay 9SR at N releases when relay 9HP picks up, and relay 9SR closes its back contacts 110 and 39. Back contact 110 of relay 9SR shifts the tuning of relay 9TR to current of the first frequency, while back contact 39 of relay 9SR conditions current of the second frequency to be supplied at N to section M—N. It follows, therefore, that the releasing of relays 6SR, 8SR and 9SR, effected when the eastbound train vacates section M—N, causes the track circuit apparatus of sections L—M and M—N to be restored to the normal condition wherein relays 7TR and 9TR are conditioned to respond to current of the first or train control frequency, and relays 6TR and 8TR are conditioned to respond to current of the second frequency.

When the train enters section O—P, relay 12TR is shunted, relays 12H and 12HP are released, and relay 12SR is provided with a stick circuit comprising back contact 74 of relay 12HP, front contact 79 and the winding of relay 12SR, and back contact 82 of relay 11SR. This stick circuit holds relay 12SR energized after the train vacates section N—O and relay 11TR operates at the 180 code rate to pick up relays 11H and 11HP. Although relay 11TR closes its front contact 30 at a rate corresponding to the code rate of energy in section N—O, track circuit energy is not, at this time, applied at O to section O—P since back contact 33 of relay 12SR is open. It follows, therefore, that when the train vacates section O—P, relay 13TR remains inactive.

Relay 14TR is shunted, relays 14H and 14D are released, and signal 14S is caused to display stop when the train enters the section extending to the right of section O—P. Relay 15TP also is caused to release and opens its front contact 86, with the result that at this time no energy is applied at P to section O—P. Energy coded at the 75 code rate is, however, applied at P to the section to the right of section O—P, and relay 15TP accordingly is caused to pick up, when this section becomes vacated, in substantially the same manner that relay 3TP is energized when the eastbound train vacates section J—K. Current of the first frequency, coded at the 75 code rate, is thereupon supplied at P to section O—P over a circuit comprising the secondary winding of line transformer LT13, front contact 44 of relay 13SR, contact 75a of coder 5CT, front contact 86 of relay 15TP, contact 4 in its back position, operated by signal 14S, and primary winding 6 of transformer 13TT. Relay 12TR accordingly operates at the 75 code rate to pick up relays 12H and 12HP, and to repeat the 75 code energy into section N—O where it causes operation of relay 10TR. Relay 10H thereupon picks up to cause signal 10S to display its approach aspect and operate its contact 4 to its front position to shift the coding of energy applied at N to section

M—N to the 180 code. This 180 code energy is repeated by relay 8TR into section L—M to cause operation of relay 6TR, whereupon relay 6D is picked up and signal 6S is caused to display its normal clear aspect.

The operation of relay 12TR at the 75 code rate, as previously mentioned, also causes the track circuit apparatus of section O—P to be restored to its normal condition effective to establish control over train-carried apparatus on a westbound train. This restoration is effected when relay 12SR releases upon relay 12HP opening its back contact 74. Back contact 33 of relay 12SR accordingly closes, and during the slow release interval of relay 12SP, current of the second frequency is supplied to section O—P at O over a circuit comprising winding 15 of transformer LT11, front contact 34 of relay 12SP, back contact 33 of relay 12SR, front contact 30 when closed of relay 11TR, and winding 6 of track transformer 12TT. This current is coded at the 180 code rate and relay 13TR accordingly operates and picks up the associated relays FSA, BSA, 13H, 13HP and 13D to cause the associated signal 13S to display its clear aspect and operate its contact 4 to its front position to shift the coding of current supplied at P to the section to the left of section O—P, to the 180 code rate. In addition, relay 13SR is released when relay 13HP picks up, the relay 13SR closes its back contacts 96 and 44. Back contact 95 tunes relay 13TR to respond to current of the first frequency, while back contact 44 shifts the frequency of current supplied at P to section O—P to the second frequency. The slow releasing characteristics of relay 12SP are selected so that relay 12SP releases at substantially the same instant that relay 13SR releases. When relay 12SP releases, back contact 114 closes to tune relay 12TR to respond to current of the second frequency, and back contact 34 closes to shift the current supplied at O to section O—P to the first frequency. It follows, therefore, that the apparatus of section O—P is restored to its normal condition wherein relay 12TR responds to current of the second frequency supplied to the associated section at end P, and relay 13TR responds to current of the first frequency supplied to the section at the opposite end O.

When signal 14S at P is caused to display its proceed or approach aspect to operate its contact member 4 from its back to its front position, the code rate of current supplied at P to section O—P is shifted from the 75 to the 180 code rate to cause relay 12TR to operate at such rate and repeat into section N—O this 180 code current, thus causing relay 10TR to operate at the 180 code rate to energize its associated relays 10H and 10D and cause the associated signal 10S to display its clear aspect. The apparatus accordingly is restored to its normal condition as represented in the drawings.

From the foregoing description, it is readily apparent that apparatus embodying my invention is arranged so as to permit an eastbound train to move through a single track stretch provided with signals so controlled by the movement of the train as to prevent opposing westbound moves while permitting following eastbound movements under permissive signal aspects governed by traffic conditions in advance. In addition, it is to be noted that such control of the signals is effected without the use of control line wires by providing each insulated section of the stretch of track with two track circuits, one of which is normally

supplied with track circuit energy of the type effective to operate train-carried apparatus and the other of which is normally supplied with track circuit energy of the type ineffective to operate train-carried apparatus. These track circuits are so arranged that whenever a train enters the stretch and shunts the rails of the first section thereof, the track circuit energies supplied to the two circuits of each section are so controlled that in each of such sections the one track circuit associated with the direction of train movement is supplied with track circuit energy of the type adapted to control train-carried apparatus, thereby rendering effective train-carried traffic controlling apparatus on a train irrespective of the direction of movement of the train on the stretch.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. In combination, a stretch of railway track including a track section, means for applying at opposite ends of said section differently characterized energies one of which has the characteristics effective for controlling train-carried apparatus, two track relays one at each end of said section, means for conditioning each of said relays to respond only to the characteristics of the energy applied at the opposite end of said section, means responsive to movement of a train on said stretch for depriving one end of said section of energy there normally applied, means effective in the event that said section is deprived of said one energy to shift the energy applied at the opposite end from the other to the said one form of energy, and means also effective for causing said conditioning means to condition said relays to respond only to energy of the characteristics applied to the opposite end of the section.

2. In combination with a stretch of railway track including a track section, signals governing traffic in opposite directions in said section, a first track relay tuned to be responsive to alternating current of one frequency and a source of alternating current of another frequency connected across the rails at one end of said section, another track relay tuned to be responsive to current of said other frequency and a source of alternating current of said one frequency connected across the rails at the opposite end of said section, means for coding the current supplied to the rails from each of said sources in accordance with traffic conditions in advance, means for controlling said signals by said two relays respectively in accordance with the rate at which current supplied to the relays is coded, means controlled by said track relays and effective when a train enters the stretch in a given direction for causing the removal of the current applied to the entrance end for the said given direction of movement, from all of the remaining sections, and means also controlled by said track relays and effective when alternating current of said one frequency is removed from the entrance end of a section for shifting the frequency of current supplied to the exit end of that section from the said other to the said one frequency, said last mentioned means also being

effective to shift the tuning of the track relays to cause each relay to be responsive only to current of the frequency applied at the opposite end of the section.

3. In combination with a stretch of railway track divided into successive adjoining track sections, each section of which has a first track relay tuned to be responsive to current of a first frequency and a source of current of a second frequency connected across the rails of the section at one end, and a second track relay tuned to be responsive to current of said second frequency and a source of current of said first frequency connected across the rails of the section at the opposite end, each section of which also has a first signal governing traffic in the section in one direction and controlled by the associated first track relay and a second signal governing traffic in the section in the opposite direction and controlled by the associated second track relay, and apparatus controlled by said track relays and effective upon a train entering said stretch and shunting the rails of the first section of said stretch for causing the removal, from all of the remaining sections, of the current normally supplied for energizing the track relays controlling the signals governing traffic in the direction opposite to that of the train movement and including means rendered effective when a section is deprived of current of said first frequency for tuning the second track relay of said section to current of said first frequency and causing the current supplied to the said one end of the section to be shifted to said first frequency, whereby to cause current of said first frequency to be supplied to the sections always in the direction to be transmitted through the track rails toward a train on said stretch.

4. An A. P. B. signal system for governing cab signals by train-carried apparatus selectively responsive to current of a first selected frequency received from the rails of a single track portion of railway track divided into a plurality of successive adjoining track sections, each section of which has a first track relay tuned to be responsive to current of a first frequency and a source of current of a second frequency connected across the rails of the section at one end, and a second track relay tuned to be responsive to current of said second frequency and a source of current of said first frequency connected across the rails of the section at the opposite end, each section of which also has a first signal governing traffic in the section in one direction and controlled by the associated first track relay and a second signal governing traffic in the section in the opposite direction and controlled by the associated second track relay, and apparatus controlled by said track relays and effective upon a train entering said stretch and shunting the rails of the first section of said stretch for causing the removal, from all of the remaining sections, of the current normally supplied for energizing the track relays controlling the signals governing traffic in the direction opposite to that of the train movement and including means rendered effective when a section is deprived of current of said first frequency for tuning the second track relay of said section to current of said first frequency and causing the current supplied to the said one end of the section to be shifted to said first frequency, whereby to cause current of said first frequency to be supplied to the sections always in the direction to be transmitted through the track rails toward a train on said stretch.

5. In combination with a stretch of railway track divided into successive adjoining track sections, each section of which has a first track relay tuned to be responsive to current of a first frequency and a source of current of a second frequency connected across the rails of the section at one end, and a second track relay tuned to be responsive to current of said second frequency and a source of current of said first frequency connected across the rails of the section at the opposite end, each section of which also has a first signal governing traffic in the section in one direction and controlled by the associated first track relay and a second signal governing traffic in the section in the opposite direction and controlled by the associated second track relay, and apparatus controlled by said track relays and effective upon a train entering said stretch and shunting the rails of the first section of said stretch for causing the removal, from all of the remaining sections, of the current normally supplied for energizing the track relays controlling the signals governing traffic in the direction opposite to that of the train movement, two stick relays at the adjacent ends of each two adjoining track sections, a first stick relay for the first track relay of one of the adjoining two sections and a second stick relay for the second track relay of the other section, means for energizing the one of said two stick relays associated with the track relay caused to be deenergized by a train entering said stretch, and means controlled by said second stick relay when energized for shifting the tuning of the associated second track relay to current of said first frequency and for shifting the current supplied to the rails at said other end of said other section to said second frequency, whereby to cause current of said first frequency to be supplied to the rails of said section in a direction always to be transmitted toward a train on said stretch.

6. In an A. P. B. railway signal system provided for a stretch of railway track divided into track sections and having means for applying alternating current energy of one frequency to the exit end of each section for one direction of traffic and simultaneously applying alternating current energy of a different frequency to the exit end of each section for the opposite direction of traffic, said system having means for coding the energy applied at each end of a section in accordance with traffic conditions in the two sections respectively adjacent thereto, the combination of, a track relay at each end of each section, tuning means for tuning each relay to be responsive to alternating current energy of the frequency applied at the opposite end of the section, apparatus controlled by said track relays and responsive to a train entering said stretch and shunting the rails of the first section thereof for removing the energy applied to the entrance end for that direction of movement, from all of the remaining sections of the stretch, and means also controlled by said track relays effective when alternating current energy of said one frequency is removed from the entrance ends of said sections for shifting the frequency of energy applied to the exit ends of said sections from said different to said one frequency and for shifting the tuning of said relays to cause them to be responsive to the shifted frequency of current applied to the opposite end of the section, whereby to apply energy of said one frequency to the sections always in the direction toward an approaching train to establish control of train-carried appa-

ratus responsive only to current of the said one frequency.

7. In an A. P. B. signal system for governing by cab signals the movements of trains through a single track portion of railway track divided into successive adjoining track sections, said trains being equipped with cab signals controlled by train-carried apparatus responsive only to alternating current energy of a preselected frequency in the track rails, said system having means for applying alternating current energy of said preselected frequency to the exit end of each section for one direction of traffic and simultaneously applying alternating current energy of another frequency to the exit end of each section for the opposite direction of traffic, said system also having means for coding the energy applied at each end of a section in accordance with traffic conditions in the two sections respectively adjacent thereto, the combination of: a track relay at each end of each section, tuning means for tuning each relay to be responsive only to alternating current energy of the frequency applied at the opposite end of the section, apparatus controlled by said track relays and responsive to a train entering said stretch and shunting the rails of the first section thereof for causing the removal of the energy applied to the entrance end for that direction of movement, from all of the remaining sections of the stretch, and means also controlled by said track relays effective when alternating current energy of said preselected frequency is removed from the entrance end of a track section for shifting the frequency of energy applied to the exit end of that section from the said other to the said preselected frequency and for shifting the tuning of the relays of that section to cause them to be responsive only to energy of the frequency applied at the opposite end of the section, whereby to apply energy of said preselected frequency to the sections always in the direction toward an approaching train.

8. In a railway signal system for governing by cab signals the movements of trains through a single track portion of railway track divided into

45

successive adjoining track sections, said trains being equipped with cab signals controlled by train-carried apparatus responsive only to alternating current energy of a preselected frequency in the track rails, said system having means for applying alternating current energy of said preselected frequency to the exit end of each section for one direction of traffic and simultaneously applying alternating current energy of another frequency to the exit end of each section for the opposite direction of traffic, said system also having means for coding the energy applied at each end of a section in accordance with traffic conditions in the two sections respectively adjacent thereto, the combination of: a track relay at each end of each section, tuning means for tuning each relay to be responsive only to alternating current energy of the frequency applied at the opposite end of the section, apparatus controlled by said track relays and responsive to a train entering said stretch and shunting the rails of the first section thereof for causing the removal of the energy applied to the entrance end for that direction of movement, from all of the remaining sections of the stretch, two stick relays at the adjacent ends of each two adjoining track sections, one of said stick relays for one direction of traffic in one of the two sections and the other of said stick relays for the opposite direction of traffic in the other section, means controlled by said track relays for energizing each of said stick relays associated with the direction of train movement, and means governed by said stick relays effective when energy of said preselected frequency is removed from the entrance end of a section for shifting the frequency of energy applied to the exit end of that section from the said other to the said preselected frequency and for shifting the tuning of the track relays of the section to cause them to be responsive only to energy of the frequency applied to the opposite end of the section, whereby to apply energy of said preselected frequency to the sections always in the direction toward an approaching train.

HERBERT A. WALLACE.
